HIS ATTORNEY.

UNITED STATES PATENT OFFICE.

LEO PRANGE, OF BROOKLYN, NEW YORK.

DESIGN FOR A BUTTON.

SPECIFICATION forming part of Design No. 21,319, dated January 26, 1892.

Application filed December 18, 1891. Serial No. 415,553. Term of patent 3½ years.

To all whom it may concern:

Be it known that I, LEO PRANGE, of Brooklyn, Kings county, and State of New York, have originated and produced a new Design 5 for Buttons, of which the following is a specification.

I will describe a button embodying my design.

In the accompanying drawings, Figure 1 is 10 a front view of a circular button embodying my design. Fig. 2 is a perspective side view thereof.

My design comprises a central figure composed of a group of jewel-shaped figures A, 15 leaf-like or petal-like figures B, extending therefrom, angular lines or rows of jewel-like figures C, and segments D, representing ropes or cords, extending between opposite angular

rows of jewel-like figures C. The surface bounded by each of the angular rows of 20 jewel-like figures C is shown as covered with radial lines.

It will be seen that the general appearance of the design is that of a cruciform figure containing a flower.

What I claim, and desire to secure by Letters Patent, is—

The design for a button, as herein shown and described.

In testimony whereof I have signed my 30 name to this specification in the presence of two subscribing witnesses.

LEO PRANGE.
